(57) CLAIM

The ornamental design for a wearable cabana, as shown and described.

DESCRIPTION

FIG. 1 shows a wearable cabana being modeled by a child in accordance with the present invention;

FIG. 2 is a second view of the wearable cabana being modeled by a child in accordance with the present invention, in its environment of use;

FIG. 3 is a perspective view thereof;

FIG. 4 is a back view thereof;

FIG. 5 is a front view thereof;

FIG. 6 is a right side view thereof;

FIG. 7 is a left side view thereof;

FIG. 8 is a top view thereof; and,

FIG. 9 is a bottom view thereof.

The broken lines on the surface of the wearable cabana depict portions of the article that form no part of the claimed design.

The broken lines showing a child and furniture represent environmental subject matter that forms no part of the claimed design.

1 Claim, 7 Drawing Sheets
